PAPER REFINING ENGINE PLUG

Homer D. Martindale, Middletown, Ohio, assignor
to The Black-Clawson Company, Hamilton,
Ohio, a corporation of Ohio

Application June 21, 1935, Serial No. 27,727

4 Claims. (Cl. 92—27)

This invention relates to paper making machines, and more particularly to Jordan engine plugs and the like.

One object of the invention is the provision 5 of a Jordan engine plug or the like, having blades and spacer woods so arranged and constructed as to give unusual strength, rigidity and long life.

Another object is the provision of a plug of 10 the character mentioned having a frusto-conical surface provided with a series of knives or blades and separators or spacers for the blades, the construction being such that the knives are held very firmly seated in the slots in a simple manner 15 by annular bands provided in surface indentations in the plug, the separators being held against radial outward movement as they are secured to the knives by cooperating longitudinal surface irregularities on the knives and spacers.

20 Another object of the invention is the provision of a plug of the character mentioned in which the surface indentations provide substantially cylindrical surfaces on the plug body, terminating in abrupt shoulders against which the bands are 25 held when the knives are moved into locking engagement with the bands.

Other objects and advantages will be apparent 30 from the following description, the appended claims and the accompanying drawings, in which—

Fig. 1 is a side elevation of a Jordan engine plug embodying the present invention;

Fig. 2 is a side elevation of one of the knives or blades with which the plug is provided;

35 Fig. 3 is a longitudinal sectional view through the outer portion of the plug taken at one side of one of the knives as indicated by the line 3—3 of Fig. 4;

Fig. 4 is a section on the line 4—4 of Fig. 3; 40 and

Fig. 5 is a perspective view of a portion of the plug showing portions of two of the knives and one of the spacers in place.

Referring more particularly to the drawings 45 by reference numerals, 10 designates generally the plug of an engine of the Jordan type such as is used in the refining of paper stock and the like. In such engines the frusto-conical plug carries a series of knives which cooperate with another series of fixed knives provided on the interior of an outer shell within which the plug is rotatably supported, the shell being of the same frusto-conical shape as the plug, and the knives on the plug and shell operating almost in 50 running contact with one another. The knives

and the knife separators which are provided between adjacent knives are usually constructed as separate pieces assembled to the conical shell of the plug.

In accordance with the present invention, there 5 is provision for very securely seating the knives in longitudinal slots provided in the frusto-conical plug shell, the latter being provided with a plurality of annular surface indentations on which knife holding bands are seated, the knives 10 having recesses on their inner sides adapted for secure interlocking engagement with the bands by moving the knives inwardly in the slots and then longitudinally along the slots, as will be 15 more fully described.

The Jordan plug 10 comprises a frusto-conical shell 11, preferably of metal. In the shell is a series of longitudinally extending slots 12 in which the knives 14 are held, the slots, as shown, 20 extending radially inwardly from the outer conical shell surface 13 with the sides of the slots parallel to one another. The inner end of each of these slots, as shown, is arcuately curved, conforming to the cylindrical curvature of the inner sides of the knives, and thus giving a very strong 25 construction at the base of the lugs which project externally from the plug body. As the circumference of the plug is considerably greater at its larger end, additional shorter slots are provided in the larger end of the plug as shown in 30 Fig. 1 to accommodate the additional shorter knives 15.

As will be more apparent from Figs. 3 and 5, the outer surface of the shell 11 is cut away so 35 as to provide a plurality of annular surface indentations 16 which extend outwardly towards the smaller end of the plug to the frusto-conical shell surface 13. At the inner end of each surface indentation 16 is a shoulder 17, which preferably extends abruptly outwardly or radially, to the shell surface 13. Seated on each of the surface indentations is an annular knife retaining band 18, each abutting against a shoulder 17 and of such size as to lie entirely below the conical surface defined by the outer surface 45 of the shell. The several bands are of similar construction although of different diameters in accordance with the different diameters of the several annular surface indentations of the shell. The inner surfaces of the bands 18 are preferably substantially cylindrical, and the surface indentations 16 are also preferably substantially cylindrical so that the bands can be readily applied merely by moving them endwise towards the larger end of the plug until they come up 50

against the respective shoulders 17. It is preferred that the bands 18 be shrunk in place to more adequately center them with the axis of rotation of the plug.

The inner surface of each of the bands 18 is spaced some distance outwardly from the inner ends of the slots 12. Each knife 14 as shown in Fig. 2, is provided with recesses 21 which are longitudinally spaced apart along the inner side 10 of the knife in accordance with the longitudinal spacing of bands 18. At one end of each of the recesses 21, the knife is extended, forming a tongue 22 for each recess and projecting toward the opposite side of the recess, as shown. The 15 width of the recess 21, at the bottom of the knife, is slightly larger than the width of the band 18, so that the knife can be inserted in the slot 12 and moving it radially inwardly and then moving it in the direction of its length toward the larger 20 end of the plug. As the knife is moved towards the larger end of the plug the tongue 22 is inserted below the band 18 where the band crosses the slot 12 in which the knife is received. The band 18 then holds the knife against radial outward movement, and gives a firm seating action 25 of the knife in the bottom of the slot, as the upper surface 23 of the projecting tongue on the knife extends at an angle to the lower edge of the knife, the angularity of the surface 23 corresponding to that of the inner surface of the band 18. That is, where the inner surface of the band 18 is cylindrical, the surface 23 on the projecting knife tongue extends parallel to the longitudinal axis of the plug, so that when the 30 knife is moved endwise toward the larger end of the plug, a wedging action will obtain between the surface 23 on the tongue and the inner surface of the ring, forcing the knife securely into the bottom of the slot. This wedging action between the knife and the band very firmly secures the 35 knife in position when the knife is moved as far as it will go toward the larger end of the plug. And since the band 18 abuts against the shoulder portion 17 of the shell, the position of the band will not be disturbed when the knife is moved in 40 the direction of its length toward the larger end of the plug, but on the contrary will only be held more tightly against the shoulder. It is, therefore, unnecessary to provide holding pins or the like to fix the position of the band on the shell, 45 and as the inside diameter of the band is such that the band can be applied in its final form preferably after first heating the band, merely by moving it over the smaller end of the shell and into abutting engagement with the shoulder 50 17 it will be apparent that the assembly of these parts is a comparatively simple operation.

It will be understood that the various bands and recesses in the knives are of similar construction although varying in diameters in accordance with the diameter of the shell at this various band location, so that the knives are simultaneously interlocked with the bands and are held down at a number of spaced points.

The normal operating force on the knives, during operation, is such as to tend to move them toward the larger end of the shell, but this tendency merely serves to tighten the wedging interlock with the encircling bands 18 and serves 60 moreover, if the bands are not perfectly tight on their seats, to more securely hold the bands 18 against their cooperating abutments or shoulders. Additional means, however, is preferably provided to prevent endwise movement of the 70 knives from their final assembled positions to-

ward the smaller end of the plug. Such movement is prevented by a holding means which may be in the form of a ring 25 which is secured as by means of shrinking it on the smaller end of the shell at the ends of the knives, one side of the ring 25 bearing against the knife ends and preventing movement of the knives. Movement of the knives towards the larger end of the shell is prevented by the wedging engagement of the knives and the bands 18, and by means of the 10 shoulders 17 which determine the position of the bands. The knives are, therefore, secured against longitudinal movement in either direction. Since they cannot move longitudinally, they cannot move outwardly in the slots in view 15 of their interlocking engagement with the several bands 18.

The knives are seated to a considerable radial distance in the slots 12, and to reinforce and separate the knives outwardly of the conical surface of the plug shell a number of separators of wood or other suitable material are employed, as shown, so as to firmly interbrace the knives out to a point a suitable distance from the outer or cutting ends. These woods or separators are 20 interlocked with the knives by means of longitudinal surface irregularities on the knives and the separators so that the latter are prevented from moving outwardly, or rising. As shown in Figs. 4 and 5, each knife is provided with a longitudinally extending projecting rib 27 at each side at a suitable location some distance out from the shell surface 13. These ribs extend parallel to the shell surface 13 and interfit with longitudinally extending depressions 28 provided 25 in the sides of the separators 29. The separators are tapered longitudinally toward the smaller end of the plug shell, in accordance with the inclination of the knives toward one another as they extend toward the smaller end of the shell. 40 The separators are positioned between adjacent knives by moving them endwise toward the smaller end of the shell and between the knives, and are driven firmly in position so as to securely interbrace the portions of the knives which project outwardly from the shell. An end plate 30 or the like may be bolted or secured to the larger end of the shell, overlapping the ends of the separators 29 and preventing their movement toward the larger end of the plug. As the projections 27 on the knives are of substantial width, the separators are securely held against outward movement, even though the outer width of the separator is greater than its width where it contacts with the shell surface. As the knives 45 are very securely held and seated in the slots by their described engagement with the holding bands 18, and as the knives are interlocked with the separators 29 it will be apparent that all 50 of the parts are firmly held together in their 60 definite predetermined positions, while the construction is such that the various parts can be readily assembled and readily constructed. The replacement of worn or damaged knives or separators can also be readily effected.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. An engine plug of the character described comprising a shell having a conical outer sur- 75

face provided with a series of longitudinally extending slots extending inwardly from the outer shell surface, and having a plurality of annular surface indentations axially spaced apart and each terminating in a shoulder which extends outwardly to the outer surface of the shell and providing a substantially cylindrical surface extending to the conical surface of the shell, a series of substantially cylindrical bands fitting on said annular surface indentations and abutting said shoulders with the inner surfaces of the bands spaced outwardly of the inside ends of the slots, said bands being located entirely within the cone defined by the outer surface of the shell, a series of knives having their inner ends fitting within said slots and having interlocking engagement with said bands preventing radial outward movement of the knives from their normal position, said knives each being adapted for insertion in one of said slots and interlocking engagement with a plurality of said bands by movement of the knife toward the plug axis and then longitudinally toward the larger end of the plug, and knife separators on the outer surface of the shell between the knives, said knife separators and knives having interlocking longitudinally extending surface irregularities holding the separators against radial outward movement.

2. An engine plug of the character described comprising a shell having a conical outer surface provided with a series of longitudinally extending slots extending inwardly from the outer shell surface, and having a plurality of annular surface indentations axially spaced apart and providing a substantially cylindrical surface extending to the conical surface of the shell, a series of substantially cylindrical bands fitting on said annular surface indentations with the inner surfaces of the bands spaced outwardly of the inside ends of the slots, said bands being located entirely within the cone defined by the outer surface of the shell, a series of knives having their inner ends fitting within and engaging the sides and bottoms of said slots and having interlocking engagement with said bands preventing radial outward movement of the knives from their normal position, said knives each being adapted for insertion in one of said slots and interlocking engagement with a plurality of said bands by movement of the knife toward the plug axis and then longitudinally toward the large end of the plug, means preventing endwise movement of said knives toward the smaller end of the plug, and a series of knife separators on the outer surface of the shell between the knives, each separator having a longitudinal surface irregularity on each side thereof interfitting with longitudinal surface irregularities of a pair of adjacent knives preventing radial outward movement of the separator.

3. A Jordan engine plug comprising a shell having a conical outer surface provided with a series of longitudinally extending deep slots extending inwardly from the outer shell surface, and having a plurality of annular surface indentations axially spaced apart and terminating toward the larger end of the plug in shoulders which extend outwardly to the outer surface of the shell, each indentation providing a substantially cylindrical surface intersecting the conical outer surface of the shell, a series of bands on said annular surface indentations and abutting said shoulders with the inner surfaces of the bands of substantially cylindrical form and spaced outwardly of the inside ends of the slots, the outer surface of each band lying within the cone defined by the outer surface of the shell, a series of knives having their inner ends fitting within said slots and having interlocking engagement with said bands preventing radial outward movement of the knives from their normal position, each knife having a recess for receiving one of said bands and having a projecting surface extending at an angle to the knife edge adapted for wedging engagement with the inner surface of the band when the knife is moved longitudinally toward the larger end of the shell.

CERTIFICATE OF CORRECTION.

Patent No. 2,146,830.

February 14, 1939.

HOMER D. MARTINDALE.

It is hereby certified that error appears in the printed specification of the above numbered patent requiring correction as follows: Page 3, first column, line 31, after the word "extending" insert deep; line 32, after "inwardly" insert a distance several times the slot width; line 33, after "surface" and before the comma insert and each terminating in a transversely curved surface so as to be devoid of sharp corners; line 43, after "ends" insert transversely curved and; and that the said Letters Patent should be read with this correction therein that the same may conform to the record of the case in the Patent Office.

Signed and sealed this 11th day of April, A. D. 1939.
